WALL FORM

George H. Brimhall, Hollywood, Calif.

Application January 18, 1940, Serial No. 314,546

2 Claims. (Cl. 25—131)

This invention relates to building construction and particularly to the method and forms whereby the walls of a building may be cast in situ.

It is particularly aimed to provide for the construction of the walls as a whole or in sections or partially, with it being possible to immediately remove and reuse the forms for further use in building the wall or walls and particularly the extension thereof.

Another object is to provide such a construction wherein the wall may be hollow or have air cells of various sizes, a construction wherein space is provided to accommodate piping, electric wiring and the like, a construction wherein the surfaces of the wall may be finished smooth, may be roughened, may simulate terra cotta paneling, in which the forms may be of metal or partly of metal and wood and are adjustable and collapsible.

It is further aimed to provide in connection with the plastic material used for the wall, for instance concrete or adobe mud, means for hastening the setting of the material, as by treating it with calcium chloride or other agent which will advance the setting of the mixture, so that the forms may be removed immediately after tamping.

Various additional objects and advantages will become apparent from a consideration of the description following taken in connection with accompanying drawings illustrating an operative embodiment.

In said drawings:

Figure 1 is a view in transverse vertical section, showing a form constructed in accordance with the invention, in position to receive the plastic material to form a portion of a wall;

Figure 2 is an elevation looking toward the inner face of the core or partition section of the form;

Figure 3 is a view in elevation looking toward the reinforced face of one of the facing sections;

Figure 4 is a partial elevation looking from the right in Figure 1;

Figure 5 is a section taken on the line 5—5 of Figure 1;

Figure 6 is a section taken on the line 6—6 of Figure 5;

Figure 7 is a horizontal section taken on the line 7—7 of Figure 5;

Figure 8 is a horizontal section taken on the line 8—8 of Figure 5;

Figure 9 is a fragmentary plan view showing the joint where cores meet at a corner;

Figure 10 is a plan view showing the inclusion of a pilaster in one of the facing sections;

Figure 11 shows a means for angularly continuing a projection form;

Figure 12 is an elevation of such projection form continuation;

Figure 13 is a plan view of a form device using channels at the ends;

Figure 14 is a side elevation of the device of Figure 13, and

Figure 15 is a longitudinal sectional view showing a tubular core which may be used to provide space within a wall casting.

The walls according to the invention are adapted to be made from concrete or a cementitious mixture or adobe clay or equivalent plastic and is preferably treated with calcium chloride or other agent to advance the setting of the mixture, so that the forms to be described, may be immediately removed after the pouring and tamping of the mixture.

Referring specifically to the drawings, I provide facing sections as at A and detailed in rear elevation in Figure 3. Such facing sections may consist of a steel or other metallic sheet 10 of any desired dimension preferably reinforced by wooden battens 11 disposed transversely thereof and connected to a longitudinal batten 12. Such battens are fastened together and to the sheet 10 as at 13 and their longitudinal edges are preferably curled or returned as at 14 and fastened as at 15 to the transverse battens 11. The outer face 16 of the sheet 10 determines the contour of the adjacent inner or outer face of the wall of the building. As shown at the left in Figure 1, such surface 16 may be plain while as shown on the sheet 10 to the right in Figure 1 it may have suitable projections 17 to correspondingly shape the adjacent face of the wall or any other desired roughening or uneven effect for the adjacent surface of the wall may be provided by varying the surface 16.

As shown in Figure 1, the facing sections A are used in pairs and spaced apart to receive the previously described plastic material between them, the plastic material being suitably tamped in place. Preferably a core construction 18 is employed between the facing sections A to provide a corresponding cell, hollow space or void in the resulting wall.

In order to connect the facing sections in operative position, anchor girts 19 are provided outwardly of such sections and at desired distances apart. Such anchor girts at top and bottom preferably have corner brackets 20 screwed in

place as at 21. Such brackets have slots 22 therethrough and cross ties in the form of strap members 24 are passed between the brackets and adjacent ends of the anchor girts and the adjacent slots 22, which straps or bars 24 have slots 25 therethrough accommodating wedges 26 having openings 27 therethrough to receive wires or other elements which may tether them to adjacent structure. The inner faces of the anchor girts have metallic bumper plates 28 screwed thereto as at 29. The facing sections A rest on the lowermost strap or bar 24. A spreader or spacer 30 is removably disposed below the uppermost strap or bar 24 being notched centrally as at 31 and at the ends as at 32, the latter notches fitting the sections A, and the former notch fitting the core 18. Resilient metallic or spring bars or strips 33 are provided in the curled or returned marginal end portions 14 of the metallic sheets 10, in intimate engagement therewith and with the adjacent ends of the battens 11, the same serving to rigidify the sections so that they will preserve their shape and the same also being adapted to extend from one section 16 to the aligned section therewith, bridging the joint between the sections and insuring accurate positioning thereof.

The core 18 has two relatively movable sections or walls 34, constructed substantially similarly to the sections A. The sections 34 have facing sheets 35 whose longitudinal edge portions are curled as at 36, around upright or transverse battens 37, and fastened thereto by screws or the like 38, with resilient steel bars or plates 39 interposed between them and the ends of the battens 37 so that they function like the bars 33. These sections 34 also include a central longitudinal batten as at 40 to give the desired reinforcement.

As best shown in Figure 6, the sections 34 are urged to slide toward each other by the action of contractile coil springs 40' whose disposition is accommodated by openings 41 in certain of the battens 37 and their terminals are anchored to the screws 38.

Spreading devices 43 are provided intermediate the sections 34 and they consist of vertical rods 44 fitted against wear plates 44' and journaled in brackets 45 screwed or otherwise fastened at 46 to adjacent battens 37. At the upper ends, said rods 44 have short sections or blocks 46' and 46'' welded thereto to increase their width while short sections or blocks 46a are welded thereto both centrally and at their lower ends. Blocks 46' are spaced from the upper ends of rods 44 so that spaces are provided to receive and guide levers 47 pivoted at 48 to rods 44, which levers preferably have heads 49 thereon. Obviously rods 44 may be hollow, solid and of any cross sectional area, and elements 46', 46'' and 46a may be integral with the rods 44 if desired. Elements 46'' and outermost lower elements 46a bear against adjacent portions 36 while the central outer element 46a engages a wear plate 46b. A removable cap 50 removably fits on top of the sections 34, within the notch 31, having depending flanges 51 engaging the outer surfaces of the sheets 35. Bumper plates 52 are preferably provided on the battens 37 at their inner surfaces, secured by screws 53. In addition, alinement of the sections 34 during lateral sliding movement is assured since studs 54 are carried by brackets 55 fastened to battens 37 and which are slidable through recesses 56 in adjacent battens. The core 18 removably rests

within a U-shaped steel tie member 56, which latter is removably disposed on the lower strap 24.

The parts are shown in Figure 1 in operative position to receive the concrete, adobe clay or other cementitious or plastic material between the sections A and the core 18, such material being adapted to be tamped in place. It is optional whether or not the core 18 is used. In its absence, a solid wall will be provided instead of a hollow or cellular wall. After the wall is tamped, calcium chloride or other agent to advance the setting of the mixture being provided, to enable the form to be at once disassembled and reused to form the continuation of the wall already cast or a portion of such wall already cast, by supporting the form on the previously cast wall.

In removing the structure, the wedges 26, which are usually driven in place, are first removed whereupon all of the parts may be readily disassembled leaving the core 18 in place. Such core is disassembled by removing the cap 31 and then swinging the levers 47 upwardly and then turning the same to rotate the rods 44 on their longitudinal axes, thereby moving the blocks 46' out of spreading engagement with the other section 34, enabling the springs 40' to contract and move the sections 34 relatively close together, whereupon they may be readily lifted as a unit from the cast wall. The sections 34 are expanded simply by turning the lifted handles 47 in the opposite direction which wedges the blocks 46' against the coating sections 34, whereupon the levers 47 are lowered as in Figure 5 and the cap 31 applied.

It will be noted that blocks or spacers 53 may be interposed removably between the sections A and core 18.

Where cores 18 join at right angles, as at corners of a building, as suggested in Figure 9, the ends thereof are preferably enclosed by shields 59, suitably screwed or removably fastened to adjacent battens 37 and preferably having a portion 60 angularly disposed, so that the adjacent portion or corner of the wall may be correspondingly thickened or reinforced. In Figure 10, I show a removable section 61 having a metallic facing 62 and reinforced by battens or the like 63, which is adapted to be disposed between two of the sections A or any equivalent. It will be noted that the wall 62 is shaped so that the same will cause the formation of pilasters on the wall.

At 11 and 12, I show extensions 64 generally shaped like the projections 17 and adapted to be fastened on adjacent forms or battens, at an angle thereto, as at corners or the like, in simulating the effect of terra cotta elements. Sections 64 may have a metallic covering 65 and interior cores 66 of wood so that nails 77 may be driven through adjacent battens, the same having stops 78 thereon spaced from their heads 79, to limit their extent of penetration.

In some portions of the wall, I use the structure of Figures 13 and 14 consisting of metallic channel members 79' into the channels of which a wooden spacer 80 is disposed and fastened by means of screws at 81 and 82.

It is clear that in the formation of the wall, I may dispose in the plastic material thereof, any desired elements to later be removed to provide cells or voids or spaces for electric wiring, piping or the like. For instance I may use saturated wooden blocks, so that they may be readily

removed, and I may use tubes 83 as shown in Figure 15, the latter preferably tapering slightly.

By leaving the spreaders 30 in place and pouring around the same depressions are left just the right depth in the top of the poured wall to accommodate a strap 24 so that a steel cross tie member 56 placed in the depression brings the top of the core cover 31 parallel with the top of the sections 16 when the latter are positioned on the previous pouring, to the bottom of the depression left by the spreader 30 in the previous course, and the sections A rest on the strap 24 and are clamped up tight against the previous pouring at the bottom and against the spreader 30 by the wedges 26, at the top, in each successive course, aggregate falling into the space around the steel cross tie 56 and filling up the depression left in the previous course made by leaving spreader 30 in place and pouring around it.

Any suitable forms may be left in the walls to provide for doors, windows or the like. Also, any suitable reinforcing rods or means may be provided in the poured and tamped walls.

Various changes may be resorted to provided they fall within the spirit and scope of the invention.

I claim as my invention:

1. A form of the class described having facing

sections, a collapsible structure including means preventing movement of said sections toward each other, said sections being in plurality, spring strips connecting the pluralities of sections, the facing sections having sheets returned and engaged with said strips, reinforcing battens for the sheets engaged at their ends with said strips, the collapsible structure including anchor girts disposed against the facing sections, brackets at the corners of said anchor girts, cross ties extending through the brackets, and wedges co-acting with the cross ties and engaging the brackets.

2. A form of the class described comprising facing sections, said sections being in plurality, spring strips connecting the pluralities of sections, the facing sections having sheets returned and engaged with said strips, reinforcing battens for the sheets engaged at their ends with said strips, anchor girts disposed against the facing sections, brackets at the corners of said anchor girts upper and lower cross ties extending through the brackets, wedges co-acting with the cross ties and engaging the brackets, a tie member supported on the lower cross tie and a spreader below the upper cross tie having notches providing shoulders for abutment by the facing sections.

GEORGE H. BRIMHALL.
